ASSIGNORS, BY DIRECT AND MESNE ASSIGNMENTS, TO ADDER MACHINE COMPANY,
A CORPORATION OF PENNSYLVANIA.

MECHANICAL MOVEMENT FOR ADDING-MACHINES.

1,225,960.

Specification of Letters Patent.

Patented May 15, 1917.

Application filed December 28, 1908. Serial No. 469,529.

To all whom it may concern:

Be it known that we, JOHN PIRRONG HUNTER and HENRY KÜNTZLER, citizens of the United States, and residents of Wilkes-
5 Barre, in the county of Luzerne and State of Pennsylvania, have invented certain new and useful Improvements in Mechanical Movements for Adding-Machines, of which the following is a specification.

10 Our invention relates to adding machines and more particularly to the means employed to actuate the machine when a motor is employed.

In Letters Patent of the United States, 15 No. 902,103, issued to Charles N. McFarland Oct. 27, 1908, there is shown and described a power transmitting or clutch mechanism intended to be employed in the transmission of power from a motor to an 20 adding machine. This mechanism comprises a drum actuated from a continuously rotating motor, a shaft on which the drum is loosely mounted to revolve, a carrier rigidly mounted on the shaft, a control ring mounted 25 to rotate on the shaft and provided with projecting toes, a driving arm eccentrically mounted on the carrier, means for placing a constant tension on the driving arm, a connection between the control ring and the 30 driving arm, a holder or detent adapted normally to keep the driving arm out of contact with the revolving drum inside of which the carrier is mounted, means for interrupting the function of such holder or 35 detent comprising a depressible actuator key, and means also whereby the function of the holder may be automatically restored. In effect, when the actuator key of that mechanism is depressed, the clutch shaft 40 is rotated a fraction of a revolution and such motion is adapted to be transmitted to the operative mechanism of the adding machine.

This power transmitting mechanism was 45 designed to be employed with the well known Wales adding machine and the form of motor indicated to be employed was an electric motor.

In actual practice it has been found that 50 such motors are not infrequently rendered inoperative either by accident to the motor

or to the source of energy, that changes are sometimes made in the nature of the current supplied and yet other circumstances occur which make it desirable to be able to detach and disengage the motor readily from the adding machine, and replace it by another of the same or different type, and also make it desirable to be able to detach the power transmitting devices from the operative parts of the adding machine so that they may remain idle when the machine is operated by hand. Our invention relates to means for accomplishing these purposes. It also renders possible the employment of 60 the simplest form of power transmitting mechanism, one which does not readily get out of order, is positive and certain in its movement, and which necessarily requires much less energy in its use than any mechanism now in use for this purpose.

In the drawings, Figure 1 is a side elevation, partly in section, illustrating one embodiment of our invention, as applied to a calculating machine, the machine being at 75 rest; Fig. 2 is a side elevation, partly broken away, showing the motor drive mechanism disconnected from the calculating machine, which is operable by a handle; Fig. 3 is a side elevation partly in section, 80 showing positions of the motor drive mechanism and connected parts at the end of the forward stroke of the main drive shaft; Fig. 4 is a similar view, showing the rack bar disconnected from the main drive shaft 85 of the machine; and Fig. 5 is a similar view, showing the positions of the parts during the forward stroke of the main drive shaft.

Referring to the drawings, 1 is the base of an adding machine and 2 is a part of 90 one of its side frames, of which there are two, one on each side of the machine. 3 is an operative rock shaft or main drive shaft transmitting power to the mechanism of the adding machine. Secured to this shaft, or 95 moving in harmony with it, is a lever indicated at 4 and provided with a stop foot 5 to limit its movement in one direction.

Mounted on a pair of elbow levers 20, which move together, is a depressible actuator bar or starting key 21 adapted to be moved vertically. The levers 20 are adapt-

ed to swing on pivots 22 projecting from the frame 2 of the machine. At their lower extremities they are coupled by a link 23 so that they will move together, and to one of them is pivoted a link 25 which in turn, is pivoted to a crank 26 rigidly secured to a rock shaft 27. A crank 28 secured to the rock shaft 27, is connected by a vertically placed actuator link 29 with a crank 30 mounted on a trip or rock shaft 31 which in turn, is connected to the device by which the function of the holder or detent of the power transmitting mechanism is interrupted and restored. This train of mechanism comprises the motor tripping device.

A motor is indicated at 100. A shaft 101 driven therefrom, as hereinafter described, carries a worm 102 in mesh with a worm gear 103 rigidly secured to a shell so that the gear and shell shall rotate on an intermediate clutch shaft 105 on which they are loosely mounted. A control ring provided with projecting toes 114 and slots 121 is mounted on the shaft. A holder or detent consisting of an arm 151 fast on shaft 31 is adapted to engage the toes 114 and it is provided with an arm 153 having a restoring roller 154. In the Patent No. 902103, above referred to, the coupling and clutch mechanism is fully described and such description need not be repeated here. It is sufficient to say that when the actuator bar 21 and link 29 are depressed, the clutch shaft is revolved a fraction of a revolution depending on the number and positions of the toes 114.

A lock, which forms the subject matter of another application for Letters Patent, comprises a locking arm 260 formed of an upward extension of the crank 26. This arm is provided with a slot 32 adapted to engage a pin 33 projecting from the frame of the machine to limit the movement of the arm which has a laterally projecting flange 34. Loosely mounted to oscillate at a convenient point near the arm 26, for instance on the frame 2, is a cooperating lock plate 35 having a projecting arm 36 with a lateral flange 37 adapted to engage the flange 34, and a second arm 38 having an inwardly extending flange 39 adapted to be engaged by the stop foot 5. The lock plate 35 is also provided with a slot 40 adapted to engage a pin 41 projecting from the frame 2. A spring 43 is adapted to move the arm 36 downward and the arm 38 upward.

Fig. 5 shows the actuator bar in its depressed condition. Arm 260 is in its extreme inner position and rod 29 has rocked arm 30 and shaft 31 and the clutch is thereby actuated. In the resulting movement of shaft 105, roller 154 on arm 153 is cammed forward thereby forcibly moving rod 29 upward and restoring the actuator bar 21 to its original position as indicated in Fig. 5 by the dotted lines. This movement occurs

soon after the shaft 105 has begun its movement and before the operating arm 4 of the machine has completed its oscillation. The upward movement of rod 29 and bar 21 is also accompanied by the forward movement 70 of arm 260 to the position shown in the dotted lines of the figure. As soon as the lug on this arm clears lug 37 on locking arm 36, the latter is drawn downward by the tension of spring 43 to the position indicated by the dotted lines. When the parts are in this position, the actuator bar 21 cannot be depressed as lug 37 is interposed in the path of arm 260 preventing rearward movement thereof. When the arm 4 returns to its normal position at the end of its oscillation it contacts with the foot 39 on the lower arm 38 of the locking arm 36 and thereby raises the lug 37 out of the path of arm 260, thus permitting the actuator 80 bar 21 to be again depressed. In operation, therefore, as soon as the bar 21 is depressed to cause the actuation of the machine, it is almost immediately automatically restored and locked in its elevated position until the 90 cycle of the machine is completed, whereupon the lock is released.

The motor 101 is provided with an armature shaft 1000 which is adapted to be detachably secured to the auxiliary worm shaft 95 101 by means of a coupling. In the form of device shown, this consists of a sleeve 1001 secured to the shaft 101 by a pin or bolt 1002 and which sleeve is recessed at 1003 to engage a pin 1004 projecting radially from the shaft 1000. This is a form of coupling which permits of a quick engagement and disengagement of the two shafts. Any suitable form of coupling may, however, be employed.

The power transmitting mechanism is mounted in a sub-frame 1005 and the clutch mechanism itself is arranged within a shell or inclosure 1006 to protect it from dust and injury. The frame is adapted to be detachably secured to the base 1 of the machine by bolts or screws, as indicated at 1007, or in any other suitable manner.

Mounted on the end of the shaft 101 is a motor actuator controller which forms the 115 subject matter of a separate application for Letters Patent and which, in brief, comprises a central hub, secured to or made integral with the shaft, a supporting disk 70, a plurality of radially movable weights 120 75, each provided with a circumferential flange 700 forming, in effect, a continuous annular flange adapted to expand under the influence of the centrifugal action of the motor shaft and limited in such expansion 125 by springs 79 secured to the separate weights 75 through appropriate slots in the disk 70. A locking arm 290 rigidly secured to the rock shaft 31 is provided with a tip 291 adapted to engage the flange 700 when the 130

shaft 101 is at rest. This prevents any movement of the rock shaft 31 and consequently of the actuator bar 29. When, however, the shaft 101 is revolved the centrifugal force of such revolution imparted to the weights moves them and their respective flanges radially and permits the tip 291 to pass inside of such flanges 700 and the rock shaft 31 thereafter to be oscillated.

10 The means whereby the power imparted to the intermediate clutch shaft 105 is transmitted to the operative mechanism of the adding machine will now be described.

15 Mounted on the shaft 105 and turning with it is a crank 60 having a plurality of arms 61, each provided at its outer extremity with a suitable roller 62.

20 Secured to a convenient member of the operative mechanism of the adding machine, for instance, the operative rock shaft or main drive shaft 3 is a gear 370 provided with teeth 371, so that when the gear is oscillated, the shaft 3 is oscillated by it.

25 Mounted intermediate the multiple crank 60 and the gear 370 is a floating reciprocating power transmitting member 65, one end of which lies in the path of, but not connected to the crank 60, and the opposite end having teeth to mesh with the gear 370, such 30 member serving to transmit the power from the shaft 105 to the shaft 3 when the actuator bar 21 is depressed and the clutch mechanism is rendered operative. This member 65 may, for want of a better term, be called 35 a rack bar although it will be understood that it may have a variety of forms. In the preferred form, it comprises a bar 65 having a slot 66 adapted to engage a supporting and guiding roller 63 pivoted to the clutch 40 inclosure. It also is provided with a depending arm 67 adapted to be engaged on its inner face by the rollers 62 on the crank 60 whereby it is moved in the direction indicated by the arrow in Fig. 1. On its upper 45 front edge it is provided with teeth 69 constituting a rack adapted to engage the teeth 371 of the gear 370.

50 Arranged beneath the bar 65 or on the side opposite to the teeth 69 is a movable and adjustable support and guide, consisting of a bracket 64 provided with a bolt 640, or similar means, whereby it may be secured in a slot or recess 641 formed in a bracket 1050 secured to the sub frame 1005. The 55 bracket 64 carries a roller 642 adapted to engage the edge of the bar 65, and the latter rests upon it. It will be understood that the inner edges 660 of the slot 66 are provided with a flange the better to engage the 60 roller 63 which is preferably grooved, and that the edge 68 is provided with a similar flange to engage a similar groove in the roller 642. This construction is simple and tends to secure steadiness of motion of the 65 bar 65.

When the machine is at rest, the parts are in the positions shown in Fig. 1. If now the motor 100 is energized, its shaft 1000 will be rotated and motion will be imparted to the auxiliary or worm shaft 101 through 70 the coupling 1001 and thence to the intermediate or clutch shaft 105. As the speed of rotation of the shaft 101 increases the weights 70 on the controller are spread apart by centrifugal force and the tip 291 of the 75 locking arm 290 is in a position to be pressed inwardly and to permit the rocking of the shaft 31.

Now, if the actuator bar 21 is depressed, the crank 26 is rocked and through the pivot 80 27 and crank 28, a downward motion is communicated to the actuator bar 29. This, through the crank 30, rocks the shaft 31 and, as described in the Patent 902,103, above referred to, moves the holder or detent 151 away from the toe 114 with which it has been in contact to permit the temporary coupling of the shaft 105 to the shaft 101 and the former is turned through a fraction of a revolution. In the device shown, 90 this is one-half of a revolution because there are two toes 114 diametrically placed on the ring. This movement of the shaft 105 rotates the multiple crank 60 and brings one of the rollers 62 against the inner surface 95 of the arm 67 and moves it and consequently the member 65 downward, or in the direction indicated by the arrow in Fig. 1 until, it assumes the position shown in Fig. 3. In this movement, it is guided by the roller 63 100 in the slot 66 and by the roller 642 on the bracket 64 which engages the edge 690. Its teeth 69 in mesh with the teeth 371 of the gear 370 have, however, turned the latter and oscillated the operative rock shaft 3 of 105 the machine, and such shaft has thus had imparted to it a forward stroke. The machine is provided with a heavy main spring 843 which is attached to a convenient part 110 of the frame and to arm 844 upon shaft 3, as shown in Fig. 5, and serves to retract the shaft 3 to its initial position and to compel its backward stroke. This backward stroke takes place quickly and of course tends, through the gear 370, to bring the bar 65 115 upwardly to its original position. This operation is also assisted by a spring 600 shown in Fig. 5 the operation of which is quite independent of that of the operative parts of the adding machine or of the clutch 120 mechanism.

During the downward travel of the bar 65 which imparts the forward stroke to the main drive shaft, the arm 153 is shifted to throw the arm 151 into the path of the succeeding toe 114, to disable the clutch and effect the disconnection of the worm gear 103 and the clutch shaft 105.

The arm 153 when thus shifted, returns the actuator or trip bar 21 and the actuator 130

link 29 to their normal positions, assisted by the spring 50.

On the return stroke of the main drive shaft 3, the shaft 105 has ceased to rotate, 5 and the upward travel of bar 65 brings its toe or arm 67 close to the succeeding crank roll 62.

The crank 26 and plate 35 coöperate to 10 lock the bar 21 against depression until the operative rock shaft has reached the end of its rearward stroke. The two flanges 34 and 37 are brought together by the spring 43 as the lever 4 moves forward in harmony 15 with the forward movement of the shaft 3, and they are disengaged as the foot 5 of the lever 4 engages the flange 39 on the plate 35 and moves the latter away from the crank 26. This locking mechanism forms the subject matter of a separate patent application 20 and constitutes no part of this invention.

It is evident that the operations described 25 will be repeated at each actuation of the machine brought about through the depression of the actuator bar 21.

Suppose, now, that it is desirable for any 30 reason that the motor 100 should be replaced by another motor, for instance, from one using a direct current to one using an alternating current. The motor is stopped, and 35 its shaft 1000 with the cross pin 1002 withdrawn from the sleeve 1001, and another motor with a different armature shaft may be promptly coupled to it without disturbing any of the other mechanisms of the 35 device.

Suppose that the motor is disabled, or the 40 clutch mechanism gets out of order, or some accident happens to these or other parts below the casing. With the usual type of power transmitting mechanism it would be 45 impossible to continue to use the adding machine. This is not so, however, with the described device. The bracket 64 can be moved to carry the roller to the left, as shown in Fig. 4. The bar 65 will then drop away from its engagement with the gear 370 and it will no longer be possible to transmit power through it. If now a handle is placed on the operative rock shaft 3, as indicated in Fig. 2, the adding machine may 50 be operated by hand until such time as it is desired to again operate it from the motor, when the mere adjustment of the bracket 64 and its roller 642 against the bar 65 will 55 again bring about the engagement of its teeth 69 with the teeth 371 of the gear 370 and the parts are at once in position for use.

It will be understood that the term "floating" 60 used in connection with the rack bar 65, designates a power transmission member which has no positive connection with a co-acting mechanism at least, at one end, so as to be free to move independently thereof 65 and uncontrolled thereby.

What we claim as new is:—

1. The combination in an adding machine, of an operative rock shaft, a motor, a clutch mechanism adapted to be intermittently actuated therefrom; and a floating power 70 transmission member intermediate the rock shaft and the clutch mechanism, the said member being provided with stationary guiding means.

2. The combination in an adding machine, 75 of an operative rock shaft, a motor, a clutch mechanism adapted to be intermittently actuated therefrom; and a floating, rectilinearly moving power transmission member intermediate the rock shaft and the clutch 80 mechanism unconnected with the clutch mechanism, and intermittently driven thereby to transmit power from the clutch to the rock shaft, the said member being provided with stationary guiding means. 85

3. The combination in an adding machine, of an operative rock shaft, a motor, a clutch mechanism adapted to be intermittently actuated therefrom; and a floating bar adapted 90 to be driven by the clutch to transmit power to the rock shaft in one direction only, the said bar being provided with stationary guiding means.

4. The combination in an adding machine, 95 of an operative rock shaft, a motor, a clutch mechanism adapted to be intermittently actuated therefrom; and a floating bar adapted to be driven by the clutch to transmit power to the rock shaft in one direction only.

5. The combination in an adding machine, 100 of an operative rock shaft, a motor, a clutch mechanism adapted to be intermittently actuated therefrom; a floating bar adapted to be driven by the clutch to transmit power to the rock shaft and means for restoring it 105 to its original position, the said bar being provided with stationary guiding means.

6. The combination in an adding machine, 110 of an operative rock shaft, a motor, a clutch mechanism adapted to be intermittently actuated therefrom; a floating bar adapted to be driven by the clutch to transmit power to the rock shaft in one direction; and means independent of the rock shaft for restoring it to its original position, the said bar being 115 provided with stationary guiding means.

7. The combination in an adding machine, 120 of an operative rock shaft, a motor, a clutch mechanism adapted to be intermittently actuated therefrom; a floating bar adapted to be driven by the clutch to transmit power to the rock shaft in one direction, and means moved from the rock shaft to restore it to its original position, the said bar being provided with stationary guiding means. 125

8. The combination in an adding machine, 130 of an operative rock shaft, a motor, a clutch mechanism adapted to be intermittently actuated therefrom; a floating bar adapted to be driven by the clutch in one direction

only, and a device connected with the rock shaft and adapted to be engaged by the bar to rock the shaft in the same direction, the said bar being provided with stationary guiding means.

9. The combination in an adding machine, of an operative rock shaft, a motor, a clutch mechanism adapted to be intermittently actuated therefrom; a floating bar adapted to be driven by the clutch in one direction, a device moving with the rock shaft and adapted to be engaged by the bar to rock the shaft in the same direction and means for restoring the bar to its original position.

10. The combination in an adding machine, of an operative rock shaft, a motor, a clutch mechanism adapted to be intermittently actuated therefrom; a floating bar adapted to be driven by the clutch in one direction, a device moving with the rock shaft and adapted to be engaged by the bar to move it in the same direction, and means moved from the rock shaft to restore the bar to its original position, the said bar being provided with stationary guiding means.

11. The combination in an adding machine, of an operative rock shaft, a motor, a clutch mechanism adapted to be intermittently actuated therefrom; a floating bar adapted to be driven by the clutch in one direction, a device moving with the rock shaft and adapted to be engaged by the bar to rock the shaft in the same direction and means for restoring the bar to its original position; and further means moved from the rock shaft to assist in such restoration, the said bar being provided with stationary guiding means.

12. The combination in an adding machine, of an operative rock shaft, a motor, a clutch mechanism adapted to be intermittently actuated, a device on the rock shaft and moving with it; a floating member adapted to be moved from the clutch to engage such device and rock the shaft, and means to guide such floating member.

13. The combination in an adding machine, of an operative rock shaft, a motor, a clutch mechanism adapted to be intermittently actuated, a device on the rock shaft and moving with it, a floating member adapted to be driven from the clutch to engage such device and rock the shaft; and means for maintaining such engagement, the said member being provided with stationary guiding means.

14. The combination in an adding machine, of an operative rock shaft, a motor, a clutch mechanism adapted to be intermittently actuated, a device on the rock shaft and moving with it, a floating member adapted to be driven from the clutch to engage such device and rock the shaft; and

removable means for maintaining such engagement, the said member being provided with stationary guiding means.

15. The combination in an adding machine, of an operative rock shaft, a motor, a clutch mechanism adapted to be intermittently actuated, a device on the rock shaft and moving with it, and a floating member adapted to be driven from the clutch to engage such device and rock the shaft.

16. The combination in an adding machine, of an operative rock shaft, a gear adapted to actuate the latter, a rack bar adapted to engage the gear, a motor, a clutch adapted to be actuated therefrom and a crank driven by the clutch to engage the rack bar and move it in one direction.

17. The combination in an adding machine, of an operative rock shaft, a gear adapted to actuate the latter, a rack bar adapted to engage the gear, a motor, a clutch adapted to be actuated therefrom and a crank driven by the clutch to engage the rack bar and move it in one direction, and independent means to restore the bar to its original position.

18. The combination in an adding machine, of an operative rock shaft, a gear adapted to actuate the latter, a rack bar adapted to engage the gear, a motor, a clutch adapted to be actuated therefrom, a crank driven by the clutch to engage the rack bar and move it in one direction, and means to restore the rack bar to its original position, comprising a spring secured to a fixed portion of the clutch enclosure and to the rack bar.

19. The combination in an adding machine, of an operative rock shaft, a gear adapted to actuate the latter, a rack bar adapted to engage the gear, a motor, a clutch adapted to be actuated therefrom and a crank driven by the clutch to engage the rack bar and move it in one direction, independent means to restore the bar to its original position; and a second means also adapted to restore the bar to its original position.

20. The combination in an adding machine, of an operative rock shaft, a motor, a clutch mechanism adapted to be intermittently actuated therefrom; a floating bar adapted to be driven by the clutch to transmit power to the rock shaft; and a guide and support for the bar and shiftable to disable the bar.

21. The combination in an adding machine, of an operative rock shaft, a motor, a clutch mechanism adapted to be intermittently actuated therefrom; a floating bar adapted to be driven by the clutch to transmit power to the rock shaft, and a guide and support adjustable to disable the bar.

22. The combination in an adding machine, of an operative rock shaft, a motor,

6
a clutch mechanism adapted to be intermittently actuated therefrom; a floating bar adapted to be driven by the clutch in one direction only; and a device moving with the rock shaft and adapted to be engaged by the bar to move it in the same direction.

23. The combination in an adding machine, of an operative rock shaft, a continuously running motor, a clutch mechanism adapted to be actuated at the will of the operator, including an intermediate shaft rotated from the motor, a crank moved by said intermediate shaft; and a floating member adapted to be driven from the crank and to impart motion to the operative rock shaft.

24. The combination in an adding machine, of an operative rock shaft, a continuously running motor, a clutch mechanism adapted to be actuated at the will of the operator, including an intermediate shaft rotated from the motor, a crank moved by said intermediate shaft; a floating member adapted to be driven from the crank and to impart motion to the operative rock shaft and means for returning the floating member to normal position after the intermediate shaft makes a fraction of a revolution.

25. The combination in an adding machine, of an operative rock shaft, a continuously running motor, a clutch mechanism adapted to be actuated at the will of the operator, including an intermediate shaft rotated from the motor, a crank moved by said intermediate shaft; a floating member adapted to be driven from the crank to impart motion to the operative rock shaft; and means independent of the motor for returning the floating member to normal position after the intermediate shaft has made a fraction of a revolution.

26. The combination in an adding machine, of an operative rock shaft, a continuously running motor, a clutch mechanism adapted to be actuated at the will of the operator, including an intermediate shaft rotated from the motor, a crank moved by said intermediate shaft; a floating member adapted to be driven from the crank and to impart motion to the operative rock shaft; and means independent of the intermediate shaft for returning the floating member to normal position after the intermediate shaft has made a fraction of a revolution.

27. The combination in an adding machine, of an operative rock shaft, a continuously running motor, a clutch mechanism adapted to be actuated at the will of the operator, including an intermediate shaft rotated from the motor, a multiple-armed crank moved by said intermediate shaft, and a power transmission member adapted to be engaged by each of said arms in succession to impart motion to the operative rock shaft.

28. The combination in an adding ma-

chine of an operative rock shaft, a continuously running motor, a clutch mechanism adapted to be actuated at the will of the operator, including an intermediate shaft rotated from the motor, a multiple-armed crank moved by said intermediate shaft, a power transmission member adapted to be engaged by each of said arms in succession to impart motion to the operative rock shaft, and means for returning the power transmission member to normal position between such successive engagements.

29. The combination in an adding machine, of an operative rock shaft, a continuously running motor, a clutch mechanism adapted to be actuated at the will of the operator, including an intermediate shaft rotated from the motor; and a member adapted to be moved in a straight line to transmit power from the intermediate shaft to the operative rock shaft.

30. The combination in an adding machine, of an operative rock shaft, a continuously running motor, a clutch mechanism adapted to be actuated at the will of the operator, including an intermediate shaft rotated from the motor; and a member adapted to be moved in a straight line to transmit power from the intermediate shaft to the operative rock shaft, while the intermediate shaft is making a fraction of a revolution.

31. The combination with an adding machine, of an operative rock shaft, a continuously running motor, a clutch mechanism adapted to be actuated at the will of the operator, including an intermediate shaft rotated from the motor; and a member adapted to be moved in a straight line to transmit power from the intermediate shaft to the operative rock shaft during one half of a revolution of the intermediate shaft.

32. The combination in an adding machine, of an operative rock shaft, a continuously running motor, a clutch mechanism adapted to be actuated at the will of the operator, including an intermediate shaft rotated from the motor; a member adapted to be moved in a straight line to transmit power from the intermediate shaft to the operative rock shaft while the intermediate shaft is making a fraction of a revolution; and means for returning the power transmission member to normal position after the intermediate shaft has completed such fraction of its revolution.

33. The combination in an adding machine, of an operative rock shaft, a continuously running motor, a clutch mechanism actuated at the will of the operator, including an intermediate shaft moved by the power of the motor, and a loose connection between the intermediate shaft and the operative rock shaft whereby power is transmitted from the intermediate shaft to the

operative rock shaft when the loose connection is moving in one direction only; and stationary guides for the loose connection.

34. The combination in an adding machine, of an operative rock shaft, a continuously running motor, a clutch mechanism actuated at the will of the operator, including an intermediate shaft moved by the power of the motor, a loose connection between the intermediate shaft and the operative rock shaft whereby power is transmitted from the intermediate shaft to the operative rock shaft when the loose connection is moving in one direction only; stationary guides for the loose connection; and means for returning the loose connection to its initial position independent of the motor.

35. The combination in an adding machine, of an operative rock shaft, a continuously running motor, a clutch mechanism actuated at the will of the operator, including an intermediate shaft moved by the power of the motor, a loose connection between the intermediate shaft and the operative rock shaft whereby power is transmitted from the intermediate shaft to the operative rock shaft when the loose connection is moving in one direction only; stationary guides for the loose connection; and means for returning the loose connection to its initial position independent of the intermediate shaft.

36. The combination in an adding machine, of an operative rock shaft, a continuously running motor, a clutch mechanism actuated at the will of the operator, including an intermediate shaft moved by the power of the motor, a loose connection between the intermediate shaft and the operative rock shaft whereby power is transmitted from the intermediate shaft to the operative rock shaft to move the latter only during its forward stroke; and stationary guides for the loose connection.

37. The combination in an adding machine, of an operative rock shaft, a continuously running motor, a clutch mechanism adapted to be actuated at the will of the operator, including an intermediate shaft rotated from the motor, a crank turned by said intermediate shaft; and a floating member adapted to be driven from it to impart motion to the operative rock shaft during a partial revolution only of the crank, the said member being provided with stationary guiding means.

38. A power appliance for registering machines including a rotary prime mover, a driven member connected to the registering machine, and a power transmitting member intermediate the said prime mover and driven member adapted to reciprocate in a straight line.

39. A power appliance for registering machines comprising a continuously moving

driving element, means to obtain an intermittent supply of power therefrom, a member attached to the operating shaft of a registering machine, and an element adapted to transmit power from the said means to the said member by a reciprocal straight line movement.

40. The combination in an adding machine, of an oscillatory operating shaft; a motor; intermittent rotary driving means actuated by the motor; a driven member attached to the oscillatory shaft; and a reciprocating device to transmit power from the rotary driving means to the driven member by a straight line movement.

41. In a calculating machine, the combination with a drive shaft; a motor; clutch mechanism driven by the motor; a crank shaft driven by the clutch; and clutch-controlling mechanism; of a rack and pinion transmission between the crank shaft and drive shaft, said rack adapted to operate in a rectilinear direction.

42. In a calculating machine, the combination with a drive shaft; a motor; clutch mechanism driven by the motor; a crank shaft driven by the clutch; and clutch-controlling mechanism; of a rectilinearly shiftable transmission member between the crank shaft and drive shaft, and driven positively in one direction by the crank shaft to impart a forward stroke to the drive shaft; and means brought into action by the forward stroke of the drive shaft to restore the transmission member to its initial position.

43. In a calculating machine, the combination with a drive shaft; a motor; clutch mechanism driven by the motor; a crank shaft driven by the clutch; and clutch-controlling mechanism; of an angular transmission member between the crank shaft and drive shaft; the crank shaft adapted to wipe against one arm of the transmission member to positively shift the latter in one direction to turn the drive shaft forwardly, and then release the transmission member; and means to operate after the release of the transmission member to restore it to initial position.

44. In a calculating machine, the combination with a drive shaft; a motor; clutch mechanism driven by the motor; and clutch-controlling mechanism; of a transmission member between the clutch mechanism and drive shaft, and adjustable into and out of effective relation with the drive shaft.

45. In a calculating machine, the combination with a drive shaft; transmission mechanism including a clutch member and a worm shaft, to turn the drive shaft; clutch-controlling means; and a motor including an armature shaft, to operate the transmission mechanism; of a releasable connection between the armature and worm shafts comprising a socket sleeve fast on one of said

shafts and having a slot therein; and a key member or pin on the remaining shaft removably seated in the slot.

46. In a calculating machine, the combination of an operative rock shaft, a motor, a clutch mechanism adapted to be intermittently actuated therefrom; a floating bar adapted to be driven by the clutch mechanism in one direction; and means connected with the rock shaft and adapted to be engaged by the bar to rock the shaft in the same direction, the said bar being provided with stationary guiding means.

47. In a calculating machine, the combination of an operative rock shaft, a motor, a clutch mechanism adapted to be intermittently actuated therefrom; a floating bar adapted to be driven by the clutch in one direction, and means connected with the rock shaft and adapted to be engaged by the bar to rock the shaft in the same direction; and means for restoring the bar to its original position; the said bar being provided with stationary guiding means.

48. In a calculating machine, the combination of an operative rock shaft, a motor, a clutch mechanism adapted to be intermittently actuated therefrom, means on the rock shaft and moving therewith, a floating power transmission member adapted to be driven from the clutch mechanism to engage such means and rock the shaft, and removable means for maintaining such engagement, said member being provided with stationary guiding means.

49. The combination in an adding machine, of an operative rock shaft; a motor; a clutch mechanism driven by the motor in one direction only; a reciprocating power transmitting member intermediate the rock shaft and clutch mechanism, and interposed in the path of and disconnected from the clutch mechanism, to be driven in one direction only by the clutch mechanism, to transmit motion to the rock shaft in only one direction; means to automatically disable the clutch mechanism at a predetermined point in the positive travel of the rock shaft; and means to restore the drive shaft and reciprocating member to their normal positions.

50. The combination in an adding machine, of an operative rock shaft; a motor; a clutch mechanism driven by the motor in one direction only; a reciprocating power transmitting member intermediate the rock shaft and clutch mechanism, and interposed in the path of and disconnected from the clutch mechanism, to be driven in one direction only by the clutch mechanism, to transmit motion to the rock shaft in only one direction; means to automatically disable the clutch mechanism at a predetermined point in the positive travel of the rock shaft; means to restore the drive shaft and reciprocating member to their normal positions;

and stationary guiding means for the reciprocating member.

51. The combination in an adding machine; with an operative rock shaft; a motor; and a clutch mechanism; of a reciprocating member intermediate the rock shaft and the clutch mechanism to stroke the rock shaft in one direction only; means to automatically disable the clutch mechanism at the end of every such stroke; means to restore the rock shaft and reciprocating member to normal; and stationary guiding means for the reciprocating member.

52. The combination in an adding machine, with an operative rock shaft; a motor; and an automatically released clutch mechanism; of a floating power transmission member intermediate the rock shaft and the clutch mechanism to stroke the rock shaft in one direction only; and means to restore the rock shaft and power transmission member to normal.

53. The combination in an adding machine, with an operative rock shaft; a motor; an automatically released clutch; and drive mechanism actuated by the clutch; of a floating power transmission member intermediate the rock shaft and clutch, one end of the power transmission member normally lying in the path of and unconnected with the drive mechanism to be contacted thereby, to stroke the rock shaft in one direction only; and means to restore the rock shaft and power transmission member to normal.

54. The combination in an adding machine, of an operative rock shaft; a motor; a clutch mechanism actuated thereby; means to automatically release the clutch mechanism at predetermined points in its rotation; a floating power transmission member intermediate the rock shaft and the clutch mechanism, and unconnected with though driven by the clutch mechanism to transmit power in one direction only to the rock shaft; and means to restore the rock shaft and power transmission member to normal.

55. The combination in an adding machine, of an operative rock shaft; a motor; a clutch mechanism actuated therefrom and normally adapted to be automatically released at a predetermined point in its rotation; a floating power transmission member intermediate the clutch mechanism and rock shaft and driven by the clutch mechanism in one direction only; and a device connected with the rock shaft and engaged by the power transmission member to rock the shaft in the same direction.

56. The combination in an adding machine, of an operative rock shaft; a motor; a clutch mechanism actuated therefrom; a floating power transmission member intermediate the clutch mechanism and rock

- shaft and driven by the clutch mechanism in one direction only; and a device connected with the rock shaft and engaged by the power transmission member to rock the shaft in the same direction. 57. The combination in an adding machine; of an operative rock shaft; a motor; a clutch mechanism actuated by the motor, and normally automatically released at a predetermined point in its travel; a device connected to the rock shaft; and a floating power transmitting member engaged with the device and adapted to be driven from the clutch in one direction only, to positively rock the shaft in one direction. 10 58. The combination in an adding machine, of an operative rock shaft; a motor; a clutch mechanism driven therefrom; means to automatically release the clutch mechanism at a predetermined point in its rotation; a device on the rock shaft and moving with it; and a floating member releasably engaged by the clutch mechanism, and positively driven thereby in one direction only, to engage and rock the shaft in one direction only. 20 59. The combination in an adding machine; of an operative rock shaft; a motor; a clutch mechanism driven therefrom; a floating bar releasably engaged by the clutch mechanism and positively driven thereby in one direction only, to engage and rock the shaft in only one direction; and shiftable supporting and guiding means for the bar. 30 60. The combination in an adding machine; of an operative rock shaft; a motor; a clutch mechanism driven therefrom; a floating bar releasably engaged by the clutch mechanism and positively driven thereby in one direction only, to engage and rock the shaft in only one direction; and means to restore the floating bar and rock shaft to their normal positions independently of the clutch mechanism. 40 61. The combination in an adding machine; of an operative rock shaft; a motor; a clutch mechanism driven therefrom; a floating bar releasably engaged by the clutch mechanism and positively driven thereby in one direction only, to engage and rock the shaft in only one direction; and means to restore the floating bar and rock shaft to their normal positions independently of the clutch mechanism, and during the time of disengagement of the clutch mechanism and floating bar. 50 62. The combination in an adding machine; of an operative rock shaft; a continuously running motor; a clutch mechanism adapted for actuation at will; and including an intermediate shaft; and a crank turned by the intermediate shaft; means to automatically release the clutch mechanism at a predetermined point in its rotation; and a floating member releasably engaged by the crank 55 and positively driven thereby to impart motion to the operative rock shaft. 63. The combination in an adding machine; of an operative rock shaft; a continuously running motor; a clutch mechanism adapted for actuation at will; and including an intermediate shaft; and a crank turned by the intermediate shaft; means to automatically release the clutch mechanism at a predetermined point in its rotation; and a floating member releasably engaged by the crank and positively driven thereby in one direction only to impart motion in one direction only to the operative rock shaft. 70 75 64. The combination in an adding machine; of an operative rock shaft; a continuously running motor; a clutch mechanism adapted for actuation at will; and including an intermediate shaft; and a crank turned by the intermediate shaft; means to automatically release the clutch mechanism at a predetermined point in its rotation; a floating member releasably engaged by the crank and positively driven thereby to impart motion to the operative rock shaft; and means to restore the rock shaft and floating member to normal positions independently of the clutch mechanism. 80 85 90 65. The combination in an adding machine; of an operative rock shaft; a continuously running motor; a clutch mechanism adapted to be actuated at the will of the operator, including an intermediate shaft driven by the motor when the clutch is effective; a crank turned by the intermediate shaft; and a floating member adapted to be releasably engaged by the crank to impart motion to the operative rock shaft. 95 100 66. The combination in an adding machine; of an operative rock shaft; a continuously running motor; a clutch mechanism adapted to be actuated at the will of the operator, including an intermediate shaft driven by the motor when the clutch is effective; a crank turned by the intermediate shaft; and a floating member adapted to be releasably engaged by the crank to impart motion to the operative rock shaft, in one direction only. 105 110 67. The combination in an adding machine; of an operative rock shaft; a continuously running motor; a clutch mechanism adapted to be actuated at the will of the operator, including an intermediate shaft driven by the motor when the clutch is effective; a crank turned by the intermediate shaft; a floating member adapted to be releasably engaged by the crank to impart motion to the operative rock shaft; and means to return the rock shaft and floating member to their normal positions. 115 120 125 68. The combination in an adding machine; of an operative rock shaft; a continuously running motor; a clutch mechanism adapted to be actuated at the will of the operator. 130

erator including an intermediate shaft driven by the motor when the clutch is effective; a crank turned by the intermediate shaft; a floating member adapted to be readily engaged by the crank to impart motion to the operative rock shaft; and means to return the rock shaft and floating member to their normal positions during the time of disengagement of the crank and floating member.

69. A power appliance for registering machines, including a prime mover rotatable in one direction only; a rocking driven member connected to the registering machine; a power transmitting member intermediate the rotary prime mover and the rocking driven member, and reciprocable in a straight line; and means interposed between the prime mover and the reciprocable power transmission member to intermittently engage the power transmission member to rock the driven member positively in one direction only.

70. A power appliance for registering machines, including a prime mover rotatable in one direction only; a rocking driven member connected to the registering machine; a power transmitting member intermediate the rotary prime mover and the rocking driven member, and reciprocable in a straight line; and means interposed between the prime mover and the reciprocable power transmission member to intermittently engage the power transmission member to rock the driven member positively in one direction only.

tently engage the power transmission member to rock the driven member positively in one direction only; and means to return the power transmission member and the driven member to normal, intermediate the effective operation of the power transmission member.

71. A power appliance for registering machines including a rotary prime mover; a driven member connected to the registering machine; and a power transmitting member intermediate the said prime mover and driven member, adapted to reciprocate in a straight line and intermittently actuated by the prime mover to positively drive the driven member in one direction only.

72. The combination in an adding machine; of an oscillatory operating shaft; a motor; intermittent rotary driving means actuated by the motor and turning in one direction only; a driven member attached to the oscillatory shaft; and a reciprocating device to transmit power from the rotary driving means to the driven member by a straight line movement in one direction only.

Witness our hands this 22nd day of December 1908, at Wilkes-Barre Pa.
